REMOTE-CONTROL SYSTEM

Ira F. Cadman, Swissvale, Pa., assignor to The Union Switch & Signal Company, Swissvale, Pa., a corporation of Pennsylvania

Application February 20, 1946, Serial No. 649,072

5 Claims. (Cl. 246—3)

1

My invention relates to remote control systems and more particularly to centralized traffic control systems in which traffic governing devices located along a trackway are governed from a control office and the conditions of the devices and associated apparatus are indicated at such office.

In systems of the type described the apparatus at the control office is linked with the traffic governing devices along the trackway by means of a communication system which may be either of the direct wire type, or of the code type, one example of which is shown in Letters Patent of the United States No. 2,229,249, granted to L. V. Lewis on January 21, 1941. In either case the communication system provides a number of control and communication channels, with the indication channels of the code system comprising separate code steps each having one distinctive character or another to indicate different conditions in the field. Two such channels are required to indicate three different conditions of a movable device. For example, a track switch is usually indicated over two channels arranged in such manner that one channel indicates whether or not the switch is locked in its normal position, and the other channel indicates whether or not the switch is locked in its reverse position. Thus when the switch is locked in either its normal or its reverse position it provides one character for the code step which indicates that the switch is locked in the corresponding position, and provides a different character for the other code step. When the switch is unlocked by the switch machine, as when the switch points are in transit between extreme positions, the code intervals of the two switch indication steps both have the different character mentioned, to indicate the transit condition. The two steps are capable of indicating a fourth condition if both have the one character referred to, but the switch obviously is not adapted to provide this character for both steps, and the full capacity of the code is ordinarily not utilized.

One object of my invention is to provide means for utilizing the two indication channels of a centralized traffic control system which indicate three conditions of a movable device, to provide an additional indication of the operation of a two-position device which otherwise would require the provision of an additional code step.

Another object of my invention is to provide means for obtaining an additional indication of either of two conditions on two indication steps of a code which are normally arranged to pro-

2

vide indications of any one of three conditions, which additional indication may be cancelled at the will of the operator to restore the system to its normal operation.

5 A specific object of my invention is to provide means for enabling apparatus provided for indicating the condition of a remotely controlled power operated track switch to indicate also the condition of the primary power supply for operating the switch. Other features of my invention will be pointed out in detail in the accompanying specification.

I shall describe one form of apparatus embodying my invention, and shall then point out 15 the novel features thereof in claims.

The accompanying drawing is a diagrammatic view illustrating one form of apparatus embodying my invention.

Referring to the drawing, a centralized traffic control system is represented as comprising control and indication apparatus at an office and at a station, and a communication system linking the office with the station.

The communication system, which may be of either the direct wire or the code system, is conventionally represented in the drawing as being a code system of the type illustrated in the previously mentioned Lewis patent. For the purposes of explaining the present invention it is sufficient to state that the communication system provides a number of control channels represented in the drawing by long-dash lines, and a number of indication channels represented in the drawing by short-dash lines, with the wires of each channel designated by reference characters which are the same as those used to designate corresponding wires in the patent. For example, the control channel 101—31 and the indication channel 113—93 represent individual code steps of a control and indication code, respectively, and the system functions in the manner explained in the patent so that if one terminal B of a suitable local source of current at the office is connected to wire 101 when a control code is transmitted, the code will include a step of a particular character corresponding to the energization of channel 101—31, to cause terminal B of a source at the station to be applied to terminal 31. Similarly, if terminal B at the station is connected to wire 93 when an indication code is transmitted, the code will include a step corresponding to the energization of channel 113—93 to apply terminal B at the office to wire 113.

55 The apparatus at the office, as indicated in the

drawing, includes a starting key SK, effective when closed to connect terminal B to wire 97, to initiate the transmission of a control code to connect terminal B to wire 29 to complete a circuit through the winding of the delivery relay D to the other terminal C of that source.

The office apparatus also includes a switch lever WK for the remote control of a power operated track switch W, lever WK having two positions for applying energy to terminal 101 or 103 respectively when starting key SK is pressed; a maintainer's call key MCK by which the operator is enabled to light a lamp MCE to call the maintainer to the telephone provided in systems of this character, key MCK being effective when closed to apply energy to terminal 105; an office delivery relay OD which is picked up at the office in response to energy applied to terminal 118 at the end of a complete indication code received from the station; and a normal indication relay NWK and a reverse indication relay RWK selectively picked up according as energy is applied to terminal 113 or 115 at the office when the office delivery relay OD is picked up. After relay NWK or RWK is picked up, it is held energized over a stick circuit including its own front contact and a back contact of relay OD, when that relay releases at the end of the indication code. To visually indicate the position of the track switch W, a normal switch indication lamp NE and a reverse indication lamp RE are provided. Each of these lamps is arranged to be energized over a circuit including a front contact of the corresponding indication relay and a back contact of the other indication relay. An additional indication lamp POE is provided at the office which is lighted to indicate the loss of the primary power supply at the station. Lamp POE is controlled over a circuit including in series front contacts 55 and 56 of relays NWK and RWK; and a single stroke bell XB, controlled by a relay XR, is caused to sound when lamp POE becomes lighted. Relay XR is energized over a circuit including front contacts 57 and 58 of relays NWK and RWK, and has a continuity transfer or make-before-break type contact 10 which is effective momentarily when relay XR picks up to close a circuit for bell XB.

The apparatus at the station for governing the operation of track switch W includes a switch locking relay LR, which is energized only when traffic conditions adjacent the switch are safe to permit operation of the switch, like the relays LMR, RMR, TR, etc., which control relay WR of the Lewis patent. The switch is manually governed by a normal switch control relay NWS and a reverse switch control relay RWS. Relay NWS or RWS, respectively, is picked up according as energy is applied to terminal 31 or 33 when delivery relay D and lock relay LR are picked up, and each switch control relay has a stick circuit including its own front contact and back contact of the other switch control relay and a back contact of delivery relay D, over which the operated switch control relay is held energized after relay D releases. The switch control relays NWS and RWS control a switch operating relay WR, which is supplied with energy of one polarity or the other according as relay NWS or RWS is picked up, provided the lock relay LR also is picked up. Relay WR controls the supply of energy to a power operated switch operating mechanism SM provided for switch W.

The primary power supply from which energy for operating the station apparatus is derived is

represented in the drawing by the reference characters ac connected to a primary winding 11 of a transformer 12 having its secondary winding 13 connected to the input terminals of a rectifier

5 R. The output terminals of rectifier R are connected across end terminals B and N of a battery 14, and normally supply rectified current to battery 14 to maintain it fully charged. A connection from terminal B to the contacts of relay 10 WR, and a return connection to terminal N provide energy for operating relay WR and the motor of switch machine SM for switch W, and connections to terminals B and C of battery 14 provide energy for operating the apparatus at the 15 switch location. The position of switch W is indicated by normal and reverse switch repeating relays NWP and RWP, which relays are selectively energized over a contact 15 operated by switch operating mechanism SM, provided switch 20 W is locked in its normal or reverse position, respectively. The continuity of the primary power supply is indicated by a power-off relay POR connected across primary winding 11 of transformer 12 and held energized as long as power is available from the alternating current source. When 25 relay POR releases, a repeating relay PORA, of the slow-pick-up type, is energized over back contact 16 of relay POR. Relay PORA governs the transmission of an indication controlling the power-off lamp POE at the office.

30 The provision of this indication is of particular advantage in connection with a power operated track switch, because in the event of a power failure it enables the operator to call the maintainer promptly, to facilitate the correction of 35 the fault and the restoration of the power supply before the switch battery 14 is fully discharged. The maintainer's call is established by a relay MCR which is energized by a control code transmitted 40 from the office when key MCK is closed, by energy applied to wire 36. When relay MCR picks up, it is held energized over a stick circuit including its contact 19, usually until released by 45 relay D, in response to a code transmitted when key MCK is open. The closing of contact 19 also completes a circuit for lamp MCE, which therefore is lighted as long as relay MCR is energized. Relay ST is the station starting relay of the code 50 system, which when picked up initiates the transmission of an indication code by connecting terminal B to wire 38, which as indicated, applies energy to the office delivery relay OD to establish the indication channels 93-113 and 95-115. A selector relay S is also operated by the code, 55 which serves to release relay ST. Relays S and ST function like the similarly designated relays of the Lewis patent, and it is to be understood that the circuits for relay ST include additional branches, not shown herein, so that relay ST becomes energized in response to each change in the 60 positions of relays NWP and RWP. Relay ST is also operated by relay D, to cause a return indication code to be transmitted following each control code.

65 The condition of the apparatus, as shown, is that obtaining when switch W has been operated to its normal position. At the office, switch lever WK is in its normal position and normal indication relay NWK is energized over its stick circuit extending from terminal B at its front contact 70 over back contact 21 of relay OD and the winding of relay NWK to terminal C; and normal switch indication lamp NE is energized over a circuit including back contact 22 of relay RWK and front contact 23 of relay NWK.

At the station, normal switch control relay NWS is energized over a circuit from terminal B at back contact 24 of relay D, over back contact 25 of relay RWS, front contact 26 and the winding of relay NWS to terminal C. The switch operating relay WR is energized in its normal direction over a circuit from terminal B at front contact 27 of relay NWS, front contact 28 of relay LR, the winding of relay WR, front contact 40 of relay LR and back contact 41 of relay RWS to terminal N. Since switch W is in its normal position, normal switch repeating relay NWP is energized over contact 15 operated by switch mechanism SM, in its normal position.

To operate switch W to its reverse position, the operator moves switch lever WK to its reverse position and presses starting key SK. Delivery relay D becomes energized and energy is applied through channel 103-33 to terminal 33 to pick up relay RWS; relay NWS being released when relay D picks up to open its back contact 24. The energization of relay RWS and deenergization of relay NWS results in the energization of switch operating relay WR by current opposite in polarity to that supplied when relay NWS is picked up and relay RWS is released, with the result that relay WR reverses its polar contacts, thereby causing the motor of switch machine SM to move switch W to its reverse position.

The switch machine SM functions in the usual manner, and its initial movement opens contact 15 as it unlocks the switch points to permit them to be moved to their reverse position, thereby releasing relay NWP. Relay ST is picked up by relay D and initiates the transmission of an indication code, and since this finds both relays NWP and RWK released, both channels 93-113 and 95-115 are deenergized to indicate the unlocked or transit condition. Consequently when the office delivery relay OD is operated, relay NWK releases and both indication lamps NE and RE become dark. When switch W reaches its reverse locked position, relay RWK is energized over contact 15, again energizing relay ST as explained in the patent, to transmit an indication code to indicate that the switch is locked reverse. In this instance channel 95-115 is supplied with energy over front contact 42 of relay RWK so that when relay OD at the office is operated, relay RWK is picked up to cause reverse switch indication lamp RE to become lighted. The operation of switch W from its reverse to its normal position is carried out in a similar manner, as will be readily understood.

It will now be assumed that a failure of the A. C. power supply occurs, when the switch is locked normal or reverse as indicated by the lighting of lamp NE or RE. Due to the loss of the A. C. power, POR releases to close its back contact 16, and relay PORA becomes energized. During the slow pick-up period of relay PORA, a circuit is closed momentarily from terminal B at back contact 50 of relay POR over back contact 51 of relay PORA to pick up starting relay ST, so that an indication code is initiated. Relay PORA picks up before the indication steps of the code are transmitted and the indication code that is transmitted under this condition results in applying energy to both wires 93 and 95 during the indication code due to the closing of front contact 52 of relay PORA to complete a connection including that contact and back contact 53 of relay MCR, between wires 93 and 95. If relay NWP is energized at this time, terminal B at back contact 42 of relay RWK is connected to wire 93

over front contact 43 of relay NWP, and from wire 93 to wire 95 over contacts 52 and 53; while if relay RWK is energized, terminal B is connected over its front contact 42 to wire 95, and from wire 95 to wire 93 over contacts 52 and 53. It follows that if the alternating current source of power should fail with the switch locked in either its normal or reverse position, channels 93-113 and 95-115 are both energized so that both relays NWK and RWK are picked up by the indication code, whereupon both switch indication lamps NE and RE become dark, and a circuit is closed including front contact 55 of relay NWK and front contact 56 of relay RWK for indication lamp POE which thereupon becomes lighted to indicate a failure of power at the station. Also, relay XR becomes energized over the circuit including front contact 57 of relay NWK and front contact 58 of relay RWK and during the transit time of contact 10 of relay XR the single stroke bell XB becomes energized to provide an audible indication of the power-off condition. Both relays NWK and RWK will, of course, be held energized by their respective stick circuits upon release of relay OD at the office, and the power-off indication will be displayed by lamp POE as long as both indication relays are energized.

It will next be assumed that a failure of the A. C. power occurs when the switch is in transit. In this case the indication code initiated by the release of relay POR finds both switch repeating relays NWP and RWK released, consequently wires 93 and 95 are deenergized and the code repeats the transit indication, lamps POE, NE and RE remaining dark. In this case, however, another indication code will be initiated in response to the energization of relay NWP or RWK as soon as the switch completes its movement and is locked by the switch machine, and since relay PORA is energized, this code will cause lamp POE to be lighted in place of lamp NE or RE, as in the preceding example.

The operator may cancel the power-off indication displayed at the office, and restore the indications normally reflecting the position of the switch, by closing the maintainer's call key MCK and momentarily pressing starting key SK. This results in the energization of relay MCR, since wire 36 at the field station becomes energized and relay MCR picks up over a circuit from terminal B at wire 36 over front contact 17 of relay D, the winding of relay MCR, front contact 18 of relay PORA and back contact 16 of relay POR. At this time front contact 19 of relay MCR closes to prepare the stick circuit for that relay and also to light the maintainer's call lamp MCE. It will be noted that this code serves as an acknowledgment of the receipt of the power-off indication by the operator, and also serves to call the maintainer to correct the fault. When relay MCR picks up, its front contact 53 opens the connection from wire 93 to 95, and since relay ST has been operated by relay D, an indication code will now be transmitted to the office reflecting receipt of the maintainer's call control code at the station. In this code, the switch indication steps will be controlled in the normal manner by switch repeating relays NWP and RWK so that either wire 93 or wire 95 will be energized according to the position of the switch. The indication code will pick up relay OD to interrupt the stick circuits for both relays NWK and RWK, and one or the other of the latter relays will be held energized over a

front contact of relay OD according as terminal 113 or 115 at the office is energized over the indication channels provided by the communication system. The energized switch indication relay at the office will, of course, light lamp NE or RE to provide the usual indication reflecting the position of the switch.

It will be seen that as long as relay POR remains released, the operator can select the power-off indication or the switch indication at will, by transmitting control codes with key MCK open or closed, respectively, and he is thus able to ascertain whether or not the power supply has been restored.

It may happen that the power failure occurs after the operator has issued a call to the maintainer, and that back contact 53 of relay MCR is open when relay POR releases. If the power should fail when relay MCR is energized, the stick circuit of relay MCR which includes back contact 18 of relay PORA is interrupted at front contact 16 of relay POR during the slow pick-up period of relay PORA, so that relay MCR releases before front contact 18 of relay PORA closes to prepare the alternative stick circuit for relay MCR, which includes front contact 18 of relay PORA, and back contact 16 of relay POR. It follows, therefore, that if relay MCR happens to be energized at the time that a power failure occurs it will be released automatically when relay POR drops, and back contact 53 of relay MCR will close and thereby enable front contact 52 of relay PORA to complete the circuit across wires 93 and 95 to indicate the power failure. This power-off indication may be cancelled by again energizing relay MCR by actuation of key MCK, as hereinbefore explained.

The apparatus embodying my invention is therefore arranged to provide an additional indication which is of advantage in maintaining a power operated track switch, by making use of the two indication steps normally provided for indicating the condition of the switch, and provides a means whereby this additional indication may be cancelled at the will of the operator to restore the switch indications. Except when this additional indication has been acknowledged and cancelled, the lighting of a switch indication lamp not only indicates the position and locked condition of the track switch, but also indicates that power is available for a considerable number of operations of the track switch.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a remote control system, an office and a station, a movable device at said station, a communication system linking said station with said office and providing two indication channels over each of which code elements of one character or another may be transmitted, means for controlling said channels by said movable device so that the code element transmitted over one channel has one character or another depending upon whether or not said device is in a first position and that transmitted over the other channel has one character or another depending upon whether or not said device is in a second position, indication means at the office controlled in accordance with the characters of said two code elements to indicate when said device is in its first

or second positions or in transit between said positions, a source of power at said field station, means for operating said movable device between its said first and second positions by power derived from said source, said operating means being manually controllable over said communication system from said office, a power-off relay at said station connected with said source to reflect presence or absence of power, means controlled by said power-off relay when reflecting absence of power for causing the code elements transmitted over said two indication channels to each have said one character, indication means at said office controlled in accordance with the character of said two elements to indicate the power-off condition, a stick relay at said station having a pick-up circuit manually controllable from said office and a stick circuit completed over either a front or a back contact of said power-off relay when said stick relay picks up, said stick circuit being interrupted momentarily to release said stick relay when said power-off relay changes its condition to reflect a change in condition of said source, and means effective when said stick relay is picked up for rendering ineffective the control by said power-off relay over the characters of said two elements, whereby not more than one of said two elements is caused to have said one character depending upon the position of said device.

2. In a remote control system, an office and a station, a first movable device at said station, a communication system linking said station with said office and providing two indication channels over which code elements of one character or another may be transmitted, means for controlling said channels by said first movable device so that the code element transmitted over one channel has one character or another depending upon whether or not said device is in a first position and that transmitted over the other channel has one character or another depending upon whether or not said device is in a second position, indication means at the office controlled in accordance with the characters of said two code elements to indicate when said device is in its first or second position or in transit between said positions, a second movable device at said station having a normal and an operated position, means controlled by said second movable device in its said operated position and effective when the code element transmitted over either of said two channels has said one character to cause the other to have said one character, indication means at said office distinctively indicating when the code elements transmitted over said two channels both have said one character, a stick relay at said station provided with a pick-up circuit manually controllable from said office and a stick circuit including its own front contact and a contact closed by said second device in either the normal or operated position of said second device, said stick circuit becoming opened momentarily to release said stick relay, if energized, when said second device moves from its normal to its operated position, and means controlled by said stick relay when energized for preventing the control of said code elements by said second device in its said operated position.

3. In combination with a power operated railway track switch manually controllable from a control office, a normal and a reverse switch repeating relay controlled by said switch and arranged to be energized only when the switch is locked in a corresponding normal or reverse posi-

tion, a normal and a reverse indication relay at said office, a communication system linking said switch repeating relays and said indication relays and providing two indication channels one for each indication relay for energizing such relay when energy is applied to the channel at said switch location, means controlled by each switch repeating relay when energized for applying energy to its channel to effect the energization of the indication relay controlled over such channel, a normal and a reverse switch indication lamp controlled by said indication relays for indicating the position of said switch, each having an energizing circuit including a front contact of the corresponding indication relay and a back contact of the other indication relay, a power-off relay at the switch location which is normally energized from the primary source of power for said switch, means controlled by said power-off relay when released for establishing a connection between said two channels at the switch location to apply energy to both channels when either switch repeating relay is energized, a power-off indication lamp at the office having an energizing circuit including front contacts of both indication relays, and means manually controllable from said office for interrupting the connection between said channels established when said power-off relay is released.

4. In combination with a power operated railway track switch, a normal and a reverse indication relay at a control office, a communication system linking said switch location with said office and providing two indication channels, one for each position of said switch, means controlled by said switch for energizing the normal or reverse indication relay over its channel only when the track switch is locked in the corresponding normal or reverse position, a power-off relay deriving its energization from the primary source of power at the switch location, means controlled by said power-off relay when released for controlling said two indication channels to energize both of said indication relays, a stick relay manu-

ally controllable from said office, means controlled by said stick relay effective if said relay is picked up after the power-off relay releases for discontinuing the control of said two indication channels by the power-off relay, means effective if the stick relay is picked up when the power-off relay is energized, for releasing the stick relay when the power-off relay releases, to render the power-off relay effective to control said two indication channels, and means at said office for visually indicating the condition of said indication relays.

5. In combination with a power operated railway track switch, a normal and a reverse indication relay at a control office, a communication system linking said switch location with said office and providing two indication channels controlled by said switch, one for energizing said normal indication relay and the other for energizing said reverse indication relay, according to the position of the switch, a power-off relay normally energized from the primary source of power at the switch location, means controlled by said power-off relay when released for controlling said two indication channels to energize both of said indication relays, a relay at said switch location manually controllable from said office and having a circuit including either a front or a back contact of said power-off relay which opens momentarily to release said manually controllable relay, if then energized in response to the release of said power-off relay, means controlled by said manually controllable relay when energized for preventing the control of said two indication channels by said power-off relay, a normal and a reverse indication lamp each having a circuit including a front contact of the corresponding indication relay and a power-off indication lamp having a circuit including front contacts of both indication relays.
